CLAIM

The ornamental design for the lamp, as shown and described.

DESCRIPTION

FIG. 1 is a perspective view from above of the lamp in accordance with my design;

FIG. 2 is a perspective view from below of the lamp in accordance with my design;

FIG. 3 is a left elevation view of the lamp in accordance with my design;

FIG. 4 is a front elevation view of the lamp in accordance with my design;

FIG. 5 is a bottom plan view of the lamp in accordance with my design; and,

FIG. 6 is a top plan view of the lamp in accordance with my design.

The right and left elevation views are substantially identical. The front and rear elevation views of the lamp housing are substantially identical. The rear elevation of the lamp back-plate is unornamented and follows the contours shown in FIGS. 1 through 6, and form no part of the claimed design.
